Patented Sept. 4, 1917.

UNITED STATES PATENT OFFICE.

MARTIN T. MINOGUE, OF PHILADELPHIA, PENNSYLVANIA.

SPARK-PLUG FOR EXPLOSIVE-ENGINES.

1,239,121.

Specification of Letters Patent.

Patented Sept. 4, 1917.

Application filed June 8, 1916. Serial No. 102,482.

To all whom it may concern:

Be it known that I, MARTIN T. MINOGUE, a citizen of the United States, residing in Philadelphia, Pennsylvania, have invented 5 certain Improvements in Spark-Plugs for Explosive-Engines, of which the following is a specification.

One object of my invention is to so construct a spark plug for explosive engines 10 as to provide for a more effective insulation than usual between the electrode or electrodes of the plug and the casing of the engine, a further object being to permit of the convenient employment of different insulating bodies in one and the same plug, and a still further object being to provide convenient connections between the electrodes of the plug and the conducting wires thereof.

In the accompanying drawing—

20 Figure 1 is a transverse section, on an enlarged scale, of a spark plug constructed in accordance with my invention;

Figs. 2 and 3 are detached perspective views of elements of said plug, and

25 Figs. 4 and 5 are transverse sections illustrating modified forms of plug embodying certain features of my invention.

The body of the plug is composed wholly or almost wholly of insulating material, that 30 form of plug shown in Fig. 1 of the drawing having inner and outer insulating members 1 and 2 of different qualities of insulating material, for instance, the inner member 1, which may for convenience be referred to 35 as the "primary" member, may well be composed of porcelain or other refractory material of high dielectric properties, while the outer member, which may be regarded as the "secondary" member, can conveniently 40 be composed of tough material which opposes more resistance to fracture than the porcelain member 1.

The secondary insulating member 2 is reduced in diameter at its lower end for insertion 45 into the shell of the valve chest or other convenient portion of the engine cylinder, and, if the material of said secondary insulating member is not such as to warrant the direct formation thereon of a thread where- 50 by it may be screwed into an internally threaded opening in said casing, the reduced portion of said secondary member is provided with a surrounding and externally threaded tubular nipple 3 of metal for this 55 purpose.

In order to insure the secure connection of

this nipple to said secondary insulating member, it projects into the body of insulating material and is molded into the same while said material is in a plastic state, the 60 material therefore passing through perforations 4 (Fig. 2) in the embedded portion of the nipple and firmly keying the same to the insulating member 2, as shown in Fig. 1.

The primary insulating member 1 may 65 also be firmly secured to the secondary insulating member 2 by molding it therein while the material of said secondary insulating member is plastic, suitable shoulders, spurs, or barbs 5 being, if desired, formed upon 70 the exterior of the primary member 1 in order to insure a firmer hold of the secondary member 2 thereon after it has been subjected to the hardening process.

Contained in the primary member 1 are 75 a pair of longitudinal electrodes 6 and 7 whose inner ends project beyond the inner end of said primary member, and, if the plug is to be used in series with another 80 plug, are so disposed in respect to one another as to form a spark gap between them. When, however, the shell of the engine is connected to one pole of the generator, the electrode 7 may be dispensed with and the spark gap may be formed between the inner 85 end of the electrode 6 and an electrode projecting from the nipple 3, as shown by dotted lines at 8, in Fig. 1, or otherwise electrically connected with the casing of the engine.

Resting upon the outer end of the secondary insulating member 2 of the plug is a cylindrical cap 2^a also, by preference, of similar insulating material, and the upper end of the electrode 6 passes freely through 95 central openings in washers 9, 10 and 11 disposed one above another at the outer end of said cap 2^a, said electrode being threaded for the reception of a confining nut 12 whereby said washers 9, 10 and 11 are 100 clamped together and to the outer end of the cap 2^a, another confining nut 13 being also adapted to the threaded outer end of the electrode 6 so as to secure the conducting wire thereto.

The washer 9 bears upon the upper end of the cap 2^a, and, between the washers 10 and 11, which are composed of insulating material, is confined the upper end of an angularly bent spring finger 14, whose upper end 110 is forked, as shown at 15 in Fig. 3, so as to straddle the electrode, and whose lower end

is likewise forked, as shown at 16 in Fig. 3, so as to engage with the grooved portion of a plunger 17 which is free to move back and forth through a notch in the side of the cap 5 2^a and through a coinciding recess in one side of the insulating member 1, said plunger being normally pressed inwardly by the spring finger 14 and being thereby maintained in contact with the upper end 10 of the electrode 7 projecting into said recess or with a plug 18 contained within said recess and engaged by the upper end of said electrode, as shown in Fig. 1.

The electrode 7 and the contact device 15 therefor just described are only employed in case the spark plug is being used as a series plug and in such case the wire communicating with the second pole of the generator may be secured to the plunger 17 by means 20 of a binding screw 19.

When desired the cap and all of the parts carried thereby can be readily removed from the plug upon first removing the nuts 12 and 13.

25 In some cases it may be advisable also to remove the primary insulating member 1 of the plug from the secondary insulating member 2 of the same, and in such case the construction shown in Fig. 4 may be adopted, 30 that is to say, the insulating member 2 may be enlarged in diameter at its inner end so as to form a shoulder 25 providing a seat for a gasket 26 interposed between the same and a shoulder 27 on the primary insulating 35 member 1 of the plug. When, therefore, upward draft upon the electrode 6 is released the primary insulating member 1 can be readily removed through the inner end of the plug.

40 When the nipple 3 is used the insulating members 1 and 2 extend completely through the same, consequently there is no possibility of a short circuit in case of fracture of the primary insulating member, within said 45 sleeve, or even of breaks in both primary and secondary insulating members in the external portion of the plug and no possibility of a short circuit between a conductor and the outer face of that portion of the plug which 50 is outwardly beyond the engine casing, and in this respect my invention overcomes a serious objection to ordinary spark plugs in which a single insulating body has a surrounding casing of metal whereby it is secured to the casing of the engine, since, in such plugs, breaks in the continuity of the insulating body almost invariably cause short circuits between the contained electrode and said outer shell.

55 In that embodiment of my invention shown in Fig. 5 the primary member 1 is enveloped by the outer or secondary member 2 except as to its inner end, and opposite recesses 20, separated by a wall of insulating material, are formed in the upper end of

said primary member, each of these recesses receiving the upper end of an electrode which engages a plug 21 having a threaded stem to which outward draft may be imparted by a nut on the outside of the insulating member 2, as shown in connection with the electrodes in Fig. 5, or, when the plug carries but a single electrode, it may have but a single bore and recess for the reception of the same. 70

I claim:

1. In a spark plug for explosive engines, a mass of insulating material constituting an integral part of the plug, said mass surrounding the electrode and extending to the 80 casing from which the plug projects, whereby the outer surface of that part of the plug which projects beyond the casing is composed wholly of insulating material.

2. In a spark plug for explosive engines, 85 the combination of a primary or internal insulator surrounding the electrode, with a secondary or external insulator surrounding said primary insulator and consisting of a mass of insulating material extending to the 90 surface of that portion of the engine casing to which the plug is applied, whereby it constitutes the outer surface of all that portion of the plug which projects beyond the engine casing. 95

3. In a spark plug for explosive engines, a mass of insulating material constituting the external portion of the plug and extending to the engine casing, in combination with a threaded nipple for screwing into said casing, all that portion of said nipple which projects beyond the casing being embedded in and surrounded by said mass of insulating material. 100

4. A spark plug for explosive engines, said 105 plug having an insulating body and a tubular nipple surrounding the inner end thereof and having a perforated portion embedded in said body of insulating material which also fills said perforations.

5. A spark plug for explosive engines, said plug consisting of a primary insulating member of porcelain and a secondary insulating member surrounding the same and composed of material which is tough and will resist fracture, said secondary member being molded directly onto the primary member. 115

6. A spark plug having an insulating member with two electrodes, one extending 120 through the outer end thereof, a plunger passing laterally into the member and in electrical connection with the other electrode, and a spring finger carrying said plunger.

7. The combination, in a spark plug for 125 explosive engines, of an insulating member having two electrodes therein, one extending through the outer end of said insulating member and the other communicating with a lateral recess therein, means for connect- 130

ing a conductor to the end of said first electrode, a plunger in electrical communication with the other electrode through the lateral recess in the insulating member, and a spring finger carrying said plunger and confined between insulating washers surrounding the first electrode.

8. The combination, in a spark plug for explosive engines, of an insulating member having two electrodes therein, one extending through the outer end of said insulating member and the other communicating with a lateral recess therein, and a detachable cap carrying a laterally movable spring-pressed plunger for contacting with the second electrode, and means carried by the first electrode for retaining said cap in position at the outer end of the plug.

10 9. The combination, in a spark plug for

explosive engines, of an insulating member having two electrodes therein, one extending through the outer end of said insulating member and the other communicating with a lateral recess therein, a detachable cap carrying a laterally movable spring-pressed plunger for contacting with the second electrode, and means carried by the first electrode for retaining said cap in position at the outer end of the plug.

15 In testimony whereof, I have signed my name to this specification, in the presence of two subscribing witnesses.

MARTIN T. MINOGUE.
